UNITED STATES PATENT OFFICE.

WILLIAM H. STEVENS, OF NEW YORK, N. Y.

CLASP.

1,345,713.

Specification of Letters Patent.

Patented July 6, 1920.

Application filed March 21, 1918. Serial No. 223,709.

To all whom it may concern:

Be it known that I, WILLIAM H. STEVENS, a citizen of the United States, residing at New York, in the county of New York and State of New York, have invented certain new and useful Improvements in Clasps, of which the following is a specification.

My invention relates to clasps adapted to support garments of various character, although it is not limited to this adaptation.

An object of my invention is to provide a garment clasp which is formed from a single piece of material, and which by virtue of its simplicity may be readily and quickly applied to effectively support various forms of garments in predetermined positions.

I will now describe one form of clasp embodying my invention, and will then point out the novel features thereof in claims.

20 In the accompanying drawings, Figure 1 is a view showing in front elevation, one form of clasp embodying my invention.

Fig. 2 is a longitudinal sectional view of the clasp shown in Fig. 1.

25 Figs. 3, 4 and 5 are views of the clasp shown in Figs. 1 and 2, showing the same applied to various forms of garments.

Similar reference characters refer to similar parts in each of the several views.

30 Referring to the drawings, the clasp is designated generally at A, and is formed from a single piece of resilient material, such as metal, celluloid or the like. As shown in Fig. 1, the clasp A is of substantially ovate formation in outline, and is curved transversely as shown in Fig. 2, so that the outer and inner sides thereof are of convex and concave formation respectively. The clasp comprises arcuate end portions 40 10, and curved side portions 11, which latter portions are of greater width than the end portions and protrude beyond the general outline of the clasp for the purpose of reinforcing the clasp, and at the same time 45 acting as bearing surfaces for the fingers to facilitate manipulation of the clasp. As the end portions 10 are narrower than the side portions 11, the clasp is weakened along its longitudinal axis, and as the clasp is curved 50 transversely, it will be evident that the clasp may be readily bent inwardly along its longitudinal axis.

Extending inwardly from each side portion 11 are integrally formed gripping 55 tongues 12, which tongues are arranged in divergent relation to each other and which

terminate at one side of the longitudinal axis of the clasp. As shown in Fig. 2, the tongues 12 are inclined upwardly or outwardly toward their free ends so that they 60 are normally disposed exteriorly of the convex side of the clasp. As shown in Fig. 1, the gripping tongues 12 formed on one side portion 11 are disposed in confronting relation to the gripping tongues formed on the other side portion, and adjacent gripping tongues are adapted to coact with each other to form clasps. The free ends of the tongues 12 are broadened to provide longitudinally extending gripping edges 13, the gripping 65 edges of adjacent tongues being arranged in spaced parallel relation but in, what I term, gripping positions. That is, the positions which the tongues assume when they are actively engaging a garment. 70

From the foregoing it will be manifest, that when the clasp is in the normal position, as shown in Fig. 1, the gripping tongues assume gripping positions, but that when they are bent inwardly toward the concave side of the clasp, they will be moved to non-gripping positions, or to positions wherein they may receive the garment to be clasped. 75

By virtue of the fact that the gripping 80 tongues are arranged in divergent relation to each other, an opening 14 of substantially diamond shaped formation is produced. This opening 14 is for the purpose of admitting and guiding a garment between the 85 gripping tongues 12.

In practice, when the clasp is used for the purpose of supporting garments of any character, a portion of the garment is gathered and passed through the opening 14, 90 while at the same time the clasp is bent along its longitudinal axis thus moving the gripping tongues to non-gripping positions and permitting the gathered portion of the garment to slip between the gripping edges 100 13. Upon releasing the clasp, the gripping tongues assume their normal or gripping positions, thus causing the gripping edges 13 to engage the garment and thereby securely retain the garment between the gripping tongues. To remove the clasp from the garment, all that is necessary is to push the gripping tongues inwardly so that they again open, but in the reverse direction, thus permitting the withdrawal of the garment, as will be understood. This clasp is such, that it may be applied with one hand, 105 110

the garment being inserted through the opening 14 by means of the thumb, while two fingers bear upon the side portions 11 thus causing the clasp to bend and opening 5 the gripping tongues to receive the garment.

Referring now to Fig. 3, I have here shown one application of the clasp wherein the same is used as a sleeve holder. As here shown, the clasp is applied vertically and 10 a gathered portion of the sleeve is passed through the opening 14, so that the sides of the gathered portion extend between the gripping tongues 12. This forms an effective sleeve holder while at the same time the 15 clasp may readily move to conform to any movement of the arm.

In Fig. 4, the clasp is used for the purpose of supporting hose, and as here shown it assumes a horizontal position, the hose 20 being gathered so that the diameter thereof is constricted to effectively engage the limb, whereupon this gathered portion is inserted into the clasp so that it slips between the gripping tongues and thus retains the hose 25 in extended position upon the limb.

In Fig. 5, is shown a further application of my invention wherein the same is used for connecting an outer shirt and under-drawers, holding down the shirt and holding up the drawers.

As here shown, the clasp A occupies a vertical position and the shirt and under-garment are gathered at corresponding 30 points and inserted so that the upper and lower pair of tongues 12 engage the under-garment and shirt respectively. The clasp 35 may be applied by first inserting the shirt and then the undergarment, so that in effect, the two garments coöperate to restrain each

other against movement by virtue of the 40 clasp.

Although I have herein shown only one form of clasp embodying my invention, it is to be understood that various changes and modifications may be made therein, without 45 departing from the spirit and scope of the appended claims.

What I claim is:

1. A device of the class described comprising a one piece transversely concaved 50 frame having a central opening therein, the end walls of said frame being weakened to permit bending of the frame along the longitudinal axis thereof, and coacting gripping tongues connected to the frame and disposed upon opposite sides of the longitudinal axis of said frame.

2. A clasp comprising a transversely concaved frame of resilient material, coacting gripping tongues formed integrally with 60 said frame, said tongues being disposed within the frame and normally occupying gripping positions, said frame being weakened along one axis to permit bending thereof to cause said gripping tongues to occupy 65 non-gripping positions.

3. A clasp comprising an ovate frame formed of resilient material, divergent gripping tongues normally occupying gripping 70 positions and disposed within and upon opposite sides of the longitudinal axis of said frame, said frame being weakened transversely to permit bending thereof longitudinally to move said gripping tongues to non-gripping positions.

In testimony whereof I affix my signature.

WILLIAM H. STEVENS.
